VACUUM BREAKER

Howard E. Reinecke, La Crescenta, Calif., assignor to Febco, Inc., Los Angeles, Calif., a corporation of California

Application December 12, 1952, Serial No. 325,529

4 Claims. (Cl. 137—217)

This invention relates to vacuum breakers and particularly to an improved form thereof having capacity to open the port thereof to atmosphere before the line pressure reaches atmospheric pressure.

It is common practice and in many cases it is required by plumbing codes to protect water service lines from contamination due to reversed flow therein caused by failure of pressure at some point therein below the highest service outlet with consequent possible intake from an opened outlet of contaminated water by the installation of vacuum breakers which open the service line to atmosphere when the line pressure drops to a predetermined point and thus prevent induction of contaminated water through a service outlet.

The primary object of the present invention is to provide a vacuum breaker which is constructed and arranged to open the air inlet port thereof at a predetermined minimum line pressure which is above atmospheric pressure.

Another object of the invention is to provide a vacuum breaker having air port valve means comprising a spring biased, ported diaphragm normally tending to open the port and a float valve means closing a port in the diaphragm when the level of water in the valve reaches the level of the diaphragm port.

A further object of the invention is to provide a vacuum breaker in which the foregoing objectives are realized in practice, which is simple in construction, economical to manufacture, and reliable in use.

With the foregoing objects in view, together with such additional objects and advantages as may subsequently appear, the invention resides in the parts, and in the construction, combination and arrangement of parts, disclosed by way of example, in the following specification of one mode of execution of the invention; reference being had to the accompanying drawings which form a part of said specification and in which drawings:

Fig. 1 is a side elevation of a vacuum breaker embodying the present invention.

Fig. 2 is an enlarged, top plan view of the vacuum breaker shown in Fig. 1 with the splash diverting cover thereof removed to show construction details.

Figs. 3, 4 and 5 are fragmentary medial sectional views taken on the line 3—3 of Fig. 2 and showing the valve in closed, partially open, and open positions, respectively, and

Fig. 6 is a top plan view taken on the lines 6—6 in Figs. 1 and 5 with the valve components in open position.

Referring to the drawings, the illustrated embodiment of the invention comprises a bottom body member 1 having a horizontally disposed flange portion 2 clamped by bolts 3 to the corresponding flange portion 4 of a top body member 5 with the rim portion 6 of a flexible diaphragm 7 interposed between said flange portions and serving as a gasket between the flanges while anchoring the diaphragm in place. The lower end of the body member 1 is provided with an inlet port 8 internally threaded for reception of a pipe P extending upwardly

2

from the highest portion of the system to be protected by the vacuum breaker and within the body member the port 8 communicates with an inverted frusto conical space 9 terminating at its upper end in the plane of the upper surface of the flange 2; the wall surface forming said space being interrupted by a plurality of vertically extending, radially disposed ribs 10 the upper faces of which are substantially horizontal and disposed slightly below the plane of the upper surface of the flange 2 and serve as limiting means for the downward movement of the diaphragm 7 as best seen in Fig. 5.

The upper body member 5 on the inner surface thereof is generally convex with the central portion 11 thereof formed as a shallow recess in which is mounted a valve seat washer 12 having a depending peripheral ridge 13 positioned for engagement with the upper surface of the diaphragm 7 when the breaker is in closed position as will be later described. Bordering the recess 11 and extending from the outer to the inner surfaces of the body member 5 are a series of sector shaped air ports 14 and between the adjacent ends of the air ports are hollow cylindrical bosses 15 closed at their upper ends and serving as housings and abutments for the upper ends of diaphragm biasing compression springs 16; the lower end of said springs fitting over upstanding bosses 17 on the upper surface of the diaphragm 7 as best shown in Figs. 3, 4 and 5. The outer walls 18 of the air ports 14 extend above the outer surface of the body member 5 and at the mid length thereof are provided with drainage slots 19. The upper ends of the bosses 15 extend above the plane of the upper edge of the walls 18 and support a splash preventing cap 20 having a downwardly projecting peripheral rim 21 disposed above and extending laterally outwardly beyond the vertical plane containing the walls 18. Screws 22 extending through the cap 20 and engaging the upper ends of the bosses 15 secure the cap 20 in position thereon.

The diaphragm 7 is provided with a centrally disposed circular opening 23 slightly smaller than the diameter of the valve seat rib 13 and embedded in the diaphragm slightly outwardly of the opening 23 and disposed directly beneath the spring engaging bosses 17 is a metal washer 24 providing stiffness to the area of the washer subjected to the action of the springs 16. A ring of thin, flexible plastic material 25' is clamped between the upper surface of the diaphragm and the flange 4 of the body member 5; the inner portion of the ring extending almost to the springs 16 as shown in Figs. 3 and 6. The plastic is much thinner than shown in the drawing, being of the order of about .007" to about .015" and has surface characteristics that do not cause it to adhere to the inner surface of the body member 5 when the valve is maintained in closed position over long periods of time as is apt to be the case with the rubber from which the diaphragm is formed.

Extending downwardly from the under surface of the body member 5 through the center of the valve seat washer 12 is a stud 25 the lower end of which extends some distance below the upper faces of the ribs 10 and loosely mounted on the stud is a disc like valve element 26 having a diameter slightly larger than the diaphragm opening 23 (see Fig. 3) and a nut 27 on the lower end of the stud 25 determines the extent of downward movement of the valve element 26. For most uses the valve element is formed of a plastic material such as polyethylene which has a specific gravity sufficiently low to enable it to float, but in some cases as will be later discussed, this valve element may be made of material of heavier specific gravity.

Assuming that the valve is installed in a system and in the absence of pressure from the system is in open position as shown in Fig. 5, on the entrance of water through the inlet port 8, the valve element will float upwardly on

the water along the stud 25 until the upper face of the valve element 26 contacts the under face of the diaphragm 7 in the region of the opening 23 therein, as shown in Fig. 4, closing that opening and thus subjecting the entire area of the diaphragm to the water pressure which then causes the diaphragm to move upwardly compressing the springs 16 until the upper face thereof adjacent the opening 23 engages the valve seat ridge 13, closing off the air ports with the static pressure on the portion of the member 26 engaging the diaphragm assisting in this sealing action; the remaining area of the diaphragm being pressed upwardly against the inner surface of the upper body member 4 as shown in Fig. 3. This is the normal position of the vacuum breaker while in service. Should the system pressure drop to a point near atmospheric pressure the springs 16 first move the diaphragm away from the air ports 14 but so long as there is water in the lower portion of the device the valve element 26 will remain in contact with the under side of the diaphragm and thus exclude the entrance of air and the escape of water. If the pressure should drop to approximately atmospheric or below, the valve element 26 will move away from the diaphragm opening and allow air to enter the system and thus prevent induction of water from an opened service outlet; the extent of downward movement of the diaphragm being limited by engagement with the ribs 10 as shown in Fig. 5.

In the above described form of the invention the action has been described in connection with the use of a valve element 26 formed of light weight material. If a heavier weight material is employed for this valve element the action in closing the valve is the same as previously described, but upon contact of the diaphragm with the valve seat element 12, the pressure on the upper and lower surface of the heavier valve element 26 becomes equalized through the clearance around the stud 25 allowing the valve element to drop to the nut 27 as indicated in dotted lines at 28 in Fig. 3. Thus upon any pressure drop sufficient to allow the springs 16 to move the diaphragm downwardly, the line is opened to admit air even though the pressure may be slightly above atmospheric. Upon the return of line pressure, the rush of water into the vacuum breaker will move the valve element upwardly into contact with the diaphragm after which the remaining closing action is the same as has been previously described. Thus, by the simple expedient of selection of the type of material, or rather by the installation of a valve element having floating or non-floating characteristics, the vacuum breaker of the present invention can be adapted to open either above or very slightly below atmospheric pressure to suit the needs of a particular installation without further change in the assembly. Further, even though service conditions may be such as to cause the diaphragm to remain in closed position over long periods of time, the interposed membrane of non-adhering material will allow the springs to immediately move the diaphragm to open the air ports when the pressure drop is sufficient to exert a lesser force against the diaphragm area than is exerted by the springs.

Since, in view of the foregoing disclosure, modifications will suggest themselves to others skilled in the art, it is not to be inferred that the invention is limited to the exact form thereof above described and it is to be understood that the invention includes all such changes and modifications in the parts, and in the construction, combination, and arrangement of parts as shall come within the purview of the appended claims.

I claim:

1. In a vacuum breaker, a hollow body structure comprising upper and lower body members having complementary bolting flanges, a flexible diaphragm having the outer edge thereof disposed between said flanges; said diaphragm having a centrally disposed opening and a rigid reinforcing member surrounding said opening and embedded in said diaphragm, a valve seat on said upper body

member positioned for engagement by said diaphragm in the area thereof adjacent to said opening, bolts connecting said flanges and said diaphragm edge, an inlet port extending through a wall of said lower body member and adapted for connection to a water service line, a series of air ports extending through a wall of said upper body member and disposed radially outwardly of said valve seat, a plurality of compression springs disposed in alternation between said air ports and extending between said upper body member and the reinforced area of said diaphragm, a vertically disposed stud carried by said upper body member extending downwardly through and below said opening in said diaphragm, a disc like valve element of greater diameter than said diaphragm opening loosely mounted on said stud below said diaphragm, and means on said stud effective to hold said valve element on said stud.

2. In a vacuum breaker, a hollow body structure comprising upper and lower body members having complementary bolting flanges, a flexible diaphragm having the outer edge thereof disposed between said flanges; said diaphragm having a centrally disposed opening and a rigid reinforcing member surrounding said opening and embedded in said diaphragm, a valve seat on said upper body member positioned for engagement by said diaphragm in the area thereof adjacent to said opening, bolts connecting said flanges and said diaphragm edge, an inlet port extending through a wall of said lower body member and adapted for connection to a water service line, a series of air ports extending through a wall of said upper body member and disposed radially outwardly of said valve seat, a plurality of compression springs disposed in alternation between said air ports and extending between said upper body member and the reinforced area of said diaphragm, a vertically disposed stud carried by said upper body member extending downwardly through and below said opening in said diaphragm, a disc like valve element of greater diameter than said diaphragm opening loosely mounted on said stud below said diaphragm, and means on said stud effective to hold said valve element on said stud.

3. In a vacuum breaker, a hollow body structure comprising upper and lower body members having complementary bolting flanges, a flexible diaphragm having the outer edge thereof disposed between said flanges; said diaphragm having a centrally disposed opening and a rigid reinforcing member surrounding said opening and embedded in said diaphragm, a valve seat on said upper body member positioned for engagement by said diaphragm in the area thereof adjacent to said opening, bolts connecting said flanges and said diaphragm edge, an inlet port extending through a wall of said lower body member and adapted for connection to a water service line, a series of air ports extending through a wall of said upper body member and disposed radially outwardly of said valve seat, a plurality of compression springs disposed in alternation between said air ports and extending between said upper body member and the reinforced area of said diaphragm, a vertically disposed stud carried by said upper body member extending downwardly through and below said opening in said diaphragm, a disc like valve element of greater diameter than said diaphragm opening loosely mounted on said stud below said diaphragm, and means on said stud effective to hold said valve element on said stud.

4. In a vacuum breaker a hollow body structure comprising an upper body member and a lower body member; said members having complementary bolting flanges provided with bolt receiving holes, a flexible diaphragm extending across the interior of said body structure and having an edge portion coextensive with said bolting flanges and disposed between said flanges, bolts extending

through said bolt receiving flanges and said edge portion of said diaphragm, a centrally disposed opening extending through said diaphragm, a plurality of air ports extending through said upper body member and disposed radially outwardly of said opening, an inlet port in said lower body member and adapted for connection to a water service line, a valve seat member carried by said upper body member and positioned for engagement by the portion of said diaphragm surrounding and adjacent to said opening, spring means tending to move said diaphragm away from said valve seat, and water flow responsive valve means comprising a stud depending from said upper body member through said diaphragm opening and a disc like valve element loosely mounted on said stud and disposed below said diaphragm operative upon flow of water

10 through said inlet port from a service line to effect initial closure of said diaphragm opening.
